Attorney

UNITED STATES PATENT OFFICE.

CHARLES H. CROSS, OF CHEYENNE, OKLAHOMA.

SAFETY CATCH FOR WATCH FOBS.

Application filed April 2, 1927. Serial No. 180,513.

This invention relates to devices for preventing watches from being picked from pockets and the specific object of this invention is to provide a device which may be engaged with the fob pocket of a pair of trousers and with the watch fob, and which will act to hold or retain the end of the watch fob in the fob pocket so that the watch will not accidentally fall out when the wearer bends over, and cannot be easily drawn from the pocket as by a pickpocket.

My invention is illustrated in the accompanying drawings wherein:—

Figure 1 is a perspective view of a safety catch constructed in accordance with my invention.

Figure 2 is a vertical sectional view of the device in applied position.

Figure 3 is a perspective view of one element of the device.

Figure 4 is a perspective view of the other element.

Referring to the drawings, it will be seen that my safety device comprises a strip of metal 10 which is formed at its middle with a transversely extending slot 11. This strip is angularly deflected at this slot as at 12 and one end of the strip is formed with a returned portion 13 which is adapted to be engaged over the upper margin of the fob pocket and clamped thereon with considerable strength, this returned portion being preferably resilient. Coacting with the member 10, which may be considered an anchoring member, is a spring catch consisting of a metallic strip bent at its middle as at 14 so as to provide two slightly divergent spring portions 15 and 16. The portion 16 is slightly curved outward and away from the portion 15 and is formed with the transversely extending ear 17 which is bent over approximately parallel to the face of the upper portion of the part 16, this upper portion 18 being relatively wide. The portion 15 is also widened at its upper end as at 19 and at its middle is angularly bent at 20. The catch is preferably made of metal as before stated. The ribbon or strap of the fob which is designated 21 is engaged with the spring catch by the transversely extending ear 17 or in any other suitable manner.

When it is desired to engage the fob with the pocket, that is, anchor the fob within the pocket, the spring catch is forced down through the slot 11 until the angular portion 20 has passed the upper wall of the slot. The portion 15 will then spring away from the portion 16 and thus the spring catch will be anchored within the strip 10 and this in turn will be held to the fob pocket. When it is desired to withdraw the spring catch from the member 10, the two parts 16 and 18 are pressed together and when so pressed together the spring catch may be withdrawn from the slot 11. It will be seen that it is a very easy matter to withdraw the spring catch from the anchoring member or engage it therewith when it is understood that the two parts 18 and 19 must be forced together against the resilience of the material from which this spring catch is made.

I claim:—

1. A safety device for watch fobs comprising an anchoring member adapted to be engaged with a pocket and having a slot and a spring catch adapted to be inserted through said slot and to be attached to the fob ribbon, the spring catch having a resilient portion extending into locking engagement with the anchoring member after the spring catch has been inserted in the slot of the anchoring member at a predetermined distance.

2. A safety device for watch fobs comprising an anchoring member formed for engagement with the pocket and having a transversely extending slot and a spring catch having means whereby it may be engaged with a fob ribbon and formed of resilient material, so formed as to provide two divergent portions resiliently urged away from each other, one of said portions having a shoulder, which when the spring catch is inserted through the slot of the anchoring member will spring outward and lock the spring catch to the anchoring member.

3. A safety device for watch fobs comprising an anchoring member formed for engagement with the pocket and having a transversely extending slot and a spring catch having means whereby it may be engaged with a fob ribbon and formed of resilient material so formed as to provide two

divergent portions resiliently urged away from each other, one of said portions having a shoulder, which when the spring catch is inserted through the slot of the anchoring member will spring outward and lock the spring catch to the anchoring member, the spring catch above the shoulder being formed

to provide two relatively wide portions adapted to be pressed together by the fingers to thus release the spring catch from its engagement with the anchoring member. 10

In testimony whereof I hereunto affix my signature.

CHARLES H. CROSS.
